UNITED STATES PATENT OFFICE.

ALBERT E. ELLIS, OF MARION, ILLINOIS.

VALVE.

Application filed November 1, 1923. Serial No. 672,213.

To all whom it may concern:

Be it known that I, ALBERT E. ELLIS, a citizen of the United States, residing at Marion, in the county of Williamson, State 5 of Illinois, have invented certain new and useful Improvements in Valves; and I do hereby declare the following to be a full, clear, and exact description of the invention, such as will enable others skilled in the art 10 to which it appertains to make and use the same.

This invention relates to new and useful improvements in valves, and particularly to valves used in mines.

15 The principal object of the invention is to provide a valve for use in the sumps of mines which is effective in its operation, and which will be proof against the attacks of acids which might be present in the water 20 in the sumps.

Other objects and advantages will be apparent from the following description when taken in connection with the accompanying drawing.

25 In the drawing:

Figure 1 is a side elevation of a valve made in accordance with the present invention.

Figure 2 is a vertical longitudinal central 30 sectional view through the valve.

Figure 3 is a vertical transverse sectional view on the line 3—3 of Figure 2.

Referring particularly to the accompanying drawing, 10 represents a cylindrical body preferably formed from wood and having a bore 11 extending through one end and terminating adjacent the other end where there is formed a transverse wall 12. In the body, and extending from the bore 40 11 through the outer face of the body, are the openings 13 which permit liquid to enter the bore. The open end of the body is formed with a reduced nipple 14 which is adapted to be engaged in the end of a conduit (not shown) which is used to convey the liquid from the sump. In the open end of the body, and at a suitable distance inwardly therefrom, is formed an opening extending from the outer face of the body 50 transversely of the bore 11, as shown at 15, and adjacent the opening, or in one wall thereof, in encircling relation to the bore, is a recess 16 in which is seated a removable centrally apertured plate 17, also of wood.

Secured in the outer face of the open end 55 of the body 10 is a bifurcated pin 18, and pivotally mounted in the bifurcation of said pin is the adjacent end of the float lever 19, said lever extending longitudinally over the body and to a suitable distance beyond the 60 other end of the body, where it is provided with a float body 20. Secured to the other end of the body, and in longitudinal alignment with the pin 18, is a somewhat longer pin 21, the said pin being formed with a 65 longitudinal slot 22 within which the lever 19 is arranged to move. Disposed for slide- 70 able movement in the opening 15, and movable transversely of the bore 11, is the valve plate 23, the end of said plate which projects from the outer end of the opening being pivotally connected with the lever 19.

It will be understood that the valve device is placed in the sump, and when the liquid rises the float lever will be moved upwardly 75 to open or raise the valve 23, thus permitting the pumps to draw the liquid from the sump, said liquid entering the bore 11 through the openings 13. When the liquid level falls the float lever will move downwardly closing the valve 23 to a degree corresponding to the level of the liquid.

Attention is called to the fact that all of the parts of the valve, including the pivots, are formed of wood thereby providing 85 against deterioration of the valve due to the presence of acids in the liquids in the sump.

What is claimed is:

A sump valve including a cylindrical 90 body the bore of which extends from a point adjacent one end through the other end, the body having openings leading from the exterior into the bore, a valve slideable in the body and transversely of the bore 95 adjacent the open end, a float lever mounted on the body and connected with the valve, the wall of the bore adjacent the valve having a groove, and a removable apertured plate disposed in said groove and against 100 which said valve slides.

In testimony whereof, I affix my signature, in the presence of two witnesses.

ALBERT E. ELLIS.

Witnesses:

JAMES R. SPILLER,
JOE KELLEY.
